Primary Examiner — Ian Simmons*Assistant Examiner* — Keith Frank(74) *Attorney, Agent, or Firm* — Paula K. Davis; Jeffrey M. Gold(57) **CLAIM**

The ornamental design for a dual-ended container, as shown.

DESCRIPTION

FIG. 1 is a perspective view of the dual-ended container showing our new design;

FIG. 2 is a front elevational view thereof, the rear being identical;

FIG. 3 is a left side elevational view thereof, the right side being identical;

FIG. 4 is a top plan view thereof; and,

FIG. 5 is a bottom plan view thereof.

The broken lines in the drawings showing of the dual-ended container illustrate the portions of the dual-ended container that form no part of the claimed design.
